HOLDER FOR FOOD PANS FOR PETS

Tony Robert, 5701 Southwest Freeway,

Houston, Tex. 77027

Filed Aug. 12, 1966, Ser. No. 3,455

Term of patent 14 years

(Cl. D12—2)

FIGURE 1 is a perspective view showing the top, one side and an end of the holder for food pans for pets, showing my new design;

I claim:

The ornamental design for a holder for food pans for pets, as shown.
